THREAD CLEANER

Samuel Hyslop, Newton, Mass.

Application May 29, 1937, Serial No. 145,475

5 Claims. (Cl. 28—68)

This invention relates to thread cleaners for removing slubs, knots, lint, snarls, and accumulations of wax-like substances and the like, from thread and yarn, while it is being wound on cones, 5 bobbins or other containers, for use in knitting and winding machines or the like.

The object of this invention is to provide an efficient and improved cleaner, having, among others, the advantages and novel features here- 10 after mentioned, including cleaner members with a much greater range of adjustability for cleaning threads and yarns of different sizes than any I know of at this time, without extra parts.

In the drawing of one embodiment of my in- 15 vention illustrated and described herein:

Fig. 1 is a front elevation, partly in section for convenience;

Fig. 2, a side elevation;

Fig. 3, a plan, with the standard cleaner mem- 20 bers positioned diagrammatically to accommodate a thread two-thousandths of an inch in diameter;

Fig. 4, a diagrammatic arrangement of the cleaner members to receive and clean a thread 25 sixteen-thousandths of an inch in diameter;

Fig. 5, a view of the cleaner disk lower face, showing the apertures that receive the disk-positioning pins; and

Fig. 6, a plan of an additional disk for use in 30 combination with one of the standard disks.

Referring to Fig. 1, my novel thread cleaner comprises a back plate 1, with suitable means, such as a curvilinear channel 2, Fig. 2, in its rear face to receive any convenient supporting mem- 35 ber, as the rod 3 on the machine, therefor, the plate having at its upper end a locking screw 4, threaded vertically therein for locking the cleaner to its support.

On its front face, the plate carries a cleaner 40 member supporting means, as the bracket 5, which is locked to the back plate as by a suitable screw 6, herein a socket head screw removable by a suitable wrench. The bracket, Fig. 1, is preferably provided with an ample vertical 45 passage 7 at its center, for the thread or yarn to travel in between the upper and lower guides 8, 9, which latter may be of any desired type, for the ready escape of lint, waste, etc.

The bracket member 5 carries two novel thread 50 cleaning members, as disks 10A and 10B, each adjustably and fixedly mounted upon the bracket by a suitable locking screw 11, herein of the socket head type, removable by a conveniently fashioned wrench, not shown, which is usually 55 in the care of the overseer, or superintendent of

the mill. The disk has a circular base section 12, with apertures 13 at convenient points therein to receive a vertical pin 14 on the upper face of the bracket 5, to thereby electively and positively position the disk axially against movement however caused, as by insecure locking, or vibration of the machine and floor, which might loosen the screw 11. The most minute adjustment, once made, is secure against disturbance. 5

The cleaner devices at present in use are ad- 10 justable to a limited extent only, either longitudinally or by turning them over, to receive thread or yarn of different sizes or numbers. Some of them have additional plates or sets of plates of different sizes, which may be substituted for the 15 original plates, to extend the range of adjustability for different thread sizes, but it is a great inconvenience and expense to be obliged to make such substitutions. In order to increase the range of thread sizes subject to cleaning action by one 20 pair of what may be called standard cleaning devices, to include most of those used by mills today, I have provided novel cleaning disks 10, drilled axially to fit accurately the screw 11, and of octagonal outline, each facet 15 of the disk 25 being a different distance from the true center of the disk.

The upper face of the disk carries near its edge and each facet a space-measuring character 17 30 as a numeral, indicating the distance of the facet radially from the true circumference of the disk, or circumference cutting the corners of the facet having the greatest radial measurement, dotted lines, Fig. 3. Obviously, when the disks are in 35 position, Fig. 3, the sum of the two numerals, one on each disk and opposite each other, and identifying certain facets, will give the width of the thread passage 18 between them, measured by any selected unit of measurement, as thousandths of an inch. 40

Herein, Fig. 3, the left-hand disk has numerals running from naught to seven, and the right-hand disk carries numerals extending from two to nine. It will be clear that, by adjusting the right-hand disk only, to position, in succession, the numerals 2 to 9, inclusive, opposite the numeral 0 on the left-hand disk, Fig. 3, eight adjustments may be made, providing electively paths for as many different sizes of thread, for instance, two thousandths to nine thousandths 50 of an inch in diameter, respectively, and by so positioning the disks as to bring together the proper numbers, as 8 on the disk 10B with 2 on the disk 10A, and then 7 on the disk 10A successively with 4 to 9, inclusive, on the disk 10B, the size of the 55

thread path may be extended to 16-thousandths of an inch. Obviously, the numerals indicating the sizes could begin with 3, instead of 2, if desired, or any other number, and extend to a correspondingly higher number.

In many mills today, however, a larger range exists in sizes of thread and yarn used, and by my novel cleaner herein described, with a supplemental disk 10C, Fig. 6, any size say, measured in thousandths of an inch, beginning with two and extending to twenty-five, may be had simply by proper adjustment of the disks. Therefore, to meet the reasonable needs of mills that spin or wind yarn of still larger sizes, or "numbers" as they are called, I may provide an additional disk 10C, Fig. 6, with facets of proper radial measurement, and bearing numerals from 9 to 16, inclusive. This disk may be substituted, if desired, for the left-hand disk 10A, and then by proper combinations of the numbers on the disks 10C and 10B, the consecutive sizes from 17 to 25, inclusive, may be accommodated. For instance, positioning the number 12 on disk 10C opposite number 5 on disk 10B, and successively thereafter with 6, 7, 8, 9, and then the number 16 on disk 10C with 6, 7, 8, and 9, respectively, on disk 10B, the path for the thread may be extended to 25 thousandths of an inch. Clearly, by combining different disks bearing different numbers, an indefinite number of combinations and increased range of sizes may be had.

Furthermore, without enlarging the disks materially, and by making the facets shorter, and thereby the thread cleaning edges shorter, nine or more facets may be provided with increased range of sizes of thread that may be used by each disk.

The great advantage of being able to use threads of practically any size within reasonable limits with one set of disks, only by the proper adjustment of them, is obvious, both with respect to convenience and the expense of the disks.

My invention is not limited to the precise construction shown herein, but may be modified in many details, without departing from the spirit of the claims, and within the scope thereof.

I claim:

1. A thread cleaner comprising a back plate with means for securing it to a support, means including centering members with an opening between them for the discharge of lint, and for supporting cleaner members in axially centered position on the back plate, and a plurality of thread cleaning members axially centered and circumferentially adjusted on said supporting means, each member having a plurality of circumferential facets of different radial measurement adapted to cooperate with a facet on a second similar member thereby to provide between them paths of different widths for the thread; and each facet having an identifying character adjacent to it indicating its distance in stated units of measurement radially from the true cleaner member circumference; means on the cleaner member supporting means and on said member to lock the member to the supporting member.

2. A thread cleaner comprising a back plate with means for securing it to a support, a bracket with cleaner disk centering means, for supporting cleaner members axially centered on the back plate; an opening in the cleaner member support for the discharge of lint, and a plurality of thread cleaning disks with cooperating centering means movably centered on said bracket and having a plurality of circumferential facets, and lockable on said bracket; and adjustable to cooperating relation with each other and thereby to provide a path of elective width for the thread between them; each facet having a distance measuring character adjacent to it indicating its distance, in known units of measurement, from the true disk circumference, whereby the sum of the two characters on opposite disk facets will indicate the distance between them; and a locking member for the cleaner for securing the latter to the bracket. 5

3. A thread cleaner comprising a back plate with means for securing it to a support, axially centering means for fixedly supporting cleaner disks on the back plate in elective position, and a plurality of thread cleaning disks on said bracket and adjustable rotatively to cooperating relation with each other, and thereby to provide a path of elective width for the thread between them each disk having a plurality of circumferential facets; each facet having a numeral 10 adjacent to it, and indicating its distance from a circle described from the disk center with a radius of sufficient length for the circle to cut a corner of the facet farthest from the disk center, whereby the sum of the two numerals on disk 15 facets opposite each other will indicate the width 20 of the thread path between them. 25

4. In a thread cleaning device for winding machines and the like, and having a member with a thread cleaning edge, a thread cleaning disk member with a plurality of facets on its edge and of different radial distances from the disk center, and means adjacent said facets indicating their distances from the true disk circumference; means for mounting the disk axially and circumferentially adjustably relative to the cleaning member edge, the member edge cooperating with the facets to provide cleaning members of predetermined variable distances apart. 30

5. A thread cleaning device comprising a back member with means for securing it to a support; a bracket on the member with cleaner disk centering means thereon, a thread cleaning disk with cooperating centering means rotatably adjustable on said bracket, the disk having a plurality of facets on its edge, each facet being a different radial distance from the disk center and disk circumference, and identifying means for said distances on the disk; a thread cleaning edge on the bracket cooperating with said thread cleaning disk edge to provide a path of selective width for the thread between them equal to the distance of the selected disk facet from the said thread cleaning edge. 55

CERTIFICATE OF CORRECTION.

Patent No. 2,126,779.

August 16, 1938.

SAMUEL HYSLOP.

It is hereby certified that error appears in the printed specification of the above numbered patent requiring correction as follows: Page 2, first column, line 54, claim 1, for "adjusted" read adjustable; and that the said Letters Patent should be read with this correction therein that the same may conform to the record of the case in the Patent Office.

Signed and sealed this 22nd day of November, A. D. 1938.

Henry Van Arsdale
